ART OF HEATING HYDROCARBONS

Eugene C. Herthel, Flossmoor, Ill., and Thomas B. Kimball, Hammond, Ind., assignors to Sinclair Refining Company, New York, N. Y., a corporation of Maine

Application February 4, 1935, Serial No. 4,826

3 Claims. (Cl. 196—110)

This invention relates to improvements in oil heating furnaces. The invention provides an oil heating furnace combining several important advantages with respect to economy of construction, economy of operation, efficiency of operation, and ease and latitude of control. This last mentioned feature of the improved oil heating furnace of this invention, ease and latitude of control, gives it special utility in the field of thermal cracking. It is, however, of general application in oil heating operations and has a similar special utility wherever ease and latitude of control are important.

The improved oil heating furnace of this invention comprises a chamber, rectangular in horizontal cross-section and substantially longer than wide, vertical heating tubes arranged in rows parallel to and spaced from the longer walls and the longer horizontal axis of the chamber, these rows of heating tubes being spaced substantially further from the longer horizontal axis of the chamber than from the nearer of the walls of the chamber, a plurality of fuel burners opening into the chamber through a series of ports along the longer axis of the roof of the chamber and between the innermost of the rows of heating tubes and means for independently regulating each of these several burners, a stack flue beneath the chamber and a port or a series of ports connecting the stack flue with the lower part of the chamber along the longer axis of the floor of the chamber and between the innermost of the rows of heating tubes. A heat radiating baffle is, with advantage, arranged along the longer horizontal axis and in the lower part of the chamber and between the innermost of the rows of heating tubes.

An oil heating furnace embodying the invention is illustrated in the accompanying drawings. In the accompanying drawings, an elevation in section of a furnace embodying the invention is shown in Fig. 1, a horizontal section of this furnace is shown in Fig. 2 and a vertical section normal to that shown in Fig. 1 is shown in Fig. 3.

The chamber of the oil heating furnace illustrated comprises two longer walls, 1 and 2, two shorter walls, 3 and 4, a roof 5 and a floor 6. Two rows, 7 and 8 and 9 and 10, of vertical heating tubes 11 are arranged along each of the longer walls 1 and 2, respectively. In the furnace illustrated, each of these rows of heating tubes is extended to a central point on the shorter wall 3. Eight fuel burners 12 open into the chamber through a corresponding series of ports 13 along the longer axis of the roof 5. The letters *a* to *h* are appended to the reference characters 12 and 13 separately to designate the several burners and the corresponding ports, respectively. The burners 12 may be of any conventional type for burning gaseous, liquid or solid fuel. Each

of these burners is provided with independent means for regulation, such as the valves 14a, 14b, 14c, 14d, etc., in the furnace illustrated. A heat radiating baffle 15 is arranged on the floor of the chamber between the pairs of rows of heating tubes. A stack flue 16, communicating with the interior of the chamber through a series of ports 17, is arranged beneath the floor 6. In the furnace illustrated, the stack flue 16, spaced below the furnace chamber, is connected to the ports 10 by means of the throat 18.

The heating tubes 11 may be connected to establish one, two or more paths of oil flow through the furnace. They may, for example, be connected to provide two symmetrical paths 15 of oil flow along each of the longer walls of the furnace chamber, but these paths of flow may take a variety of forms. For example, the heating tubes may be connected as shown in the upper half of the section constituting Fig. 2, 20 two parallel streams of oil entering the furnace at one end and being discharged at the other, or they may be connected as shown in the lower half of the section constituting Fig. 2, two parallel streams of oil entering the furnace at one end and being discharged at intermediate points 25 after flowing to the other end and back, or they may be connected as shown in the right hand part of the lower half of the section constituting Fig. 2, two parallel streams of oil entering the furnace at one end and being discharged at the same end after flowing to the other end and back. Instead of providing two rows of heating tubes along each of the longer walls, as in the furnace illustrated, one row or three or four or 30 more rows may be arranged along each of the longer walls of the furnace. Also, the tube spacing 35 may be varied along the rows and, where two or more rows are arranged along each long wall of the furnace chamber, the tube spacing 40 may be different in the different rows, for example, progressively wider spacing of the heating tubes in the second, and any following, row of tubes away from the wall of the chamber may be used to equalize heat absorption between the 45 tubes of such groups of rows. The lower ends of the heating tubes, and the lower connecting headers, are with advantage made accessible, as in the furnace illustrated (see Fig. 3), to facilitate inspection, cleaning, repair and replacement. 50

By providing a plurality of independently regulated burners along the longer horizontal axis of the furnace above a port or ports along this axis communicating with the stack flue, in accordance with the invention, the hot products 55 of combustion generated by operation of the several burners move downwardly through the furnace chamber in generally vertical paths making it possible to establish independent control of the conditions prevailing in a series of zones 60

along this axis corresponding in number to the 5 number of burners. The extent to which this subdivision of control can be carried is limited only by the number of burners used. The efficiency and capacity of the furnace remain at high values over a wide range of conditions making it possible to vary an established control without requiring, with respect to efficiency or capacity, rearrangement or reconstruction of the furnace. An individual furnace embodying this invention is thus characterized by extreme flexibility.

The vertical arrangement of the heating tubes in the oil heating furnace of the invention affords 15 the usual advantages of vertical tubes in oil heating furnaces. Further, however, the vertical arrangement of the heating tubes in effect divides the path or paths of oil flow through the furnace into a series of zones corresponding to the several 20 zones of control in the furnace chamber. The establishment and maintenance of smooth oil temperature gradients along the path or paths of oil flow through the furnace is thus facilitated. The heating tubes are also thus relieved of the 25 burden of local irregularities in rates of heat transfer through the tube walls. Uniformity in distribution of heat transfer as between the upper part and the lower part of the furnace chamber is promoted by provision of the heat radiating 30 baffle.

The following example of applications of the oil heating furnace of the invention will illustrate its utility. In reforming gasoline or gasoline-containing stocks to produce gasoline of improved 35 anti-knock value, the stock may be mildly heated over the first part of its travel through the furnace to avoid local overheating of the heating tubes particularly through the region of vaporization of the stock, intensely heated over the 40 middle part of its travel to effect the reforming and mildly heated over the last part of its travel to control and limit the extent of the reaction. In cracking gas oil to produce gasoline, the stock may be intensely heated over the first part of its 45 travel through the furnace to bring it to the cracking temperature as rapidly as possible and mildly heated over the last part of its travel, after reaching the cracking temperature, to accomplish maximum efficiency with maximum yield. In 50 viscosity breaking, the stock may be intensely heated, for maximum capacity, up to that point in its travel at which limiting metal temperatures are reached in the tubes and the heating may be controlled for the rest of its travel with respect 55 to such limiting metal temperatures. All of these operations can be carried out in a single furnace embodying this invention.

The ease and latitude of control, and the subdivision of this control, provided in the oil heating furnace of this invention materially assist in the 60 development of maximum capacities in that it makes possible the maintenance of maximum rates, per unit of area of tube wall, of heat transfer, subject only to limitations involved in the 65 processing to which the oil is being subjected, throughout the battery of heating tubes in the furnace without exceeding safe metal temperatures at any point in the battery and without requiring limitation of heat transfer rate in one 70 part of the battery to avoid exceeding safe metal temperatures in another part of the battery. The ease and latitude of control provided in the oil heating furnace of this invention similarly assist in the development of maximum efficiencies.

We claim:

1. An oil heating furnace comprising a chamber rectangular in horizontal cross-section and substantially longer than wide, vertical heating tubes arranged in rows parallel to and spaced from the longer walls and the longer horizontal axis of said chamber, said rows being spaced substantially further from said axis than from the nearer of said walls, a plurality of fuel burners opening into said chamber through a series of ports along the longer axis of the roof of said chamber and between the innermost of said rows of heating tubes, means for independently regulating said several burners, a plurality of connections between adjacent ends of pairs of said heating tubes and cooperating with said heating tubes to form a heating coil extending along the longer horizontal axis of said chamber a distance substantially greater than the distance between adjacent burners, a stack flue beneath said chamber and means connecting said stack flue and said chamber along the longer axis of the floor of said chamber and between the innermost of said rows of heating tubes. 5

2. An oil heating furnace comprising a chamber rectangular in horizontal cross-section and substantially longer than wide, vertical heating tubes arranged in rows parallel to and spaced from the longer walls and the longer horizontal axis of said chamber, said rows being spaced substantially further from said axis than from the nearer of said walls, a plurality of fuel burners opening into said chamber through a series of ports along the longer axis of the roof of said chamber and between the innermost of said rows of heating tubes, 15 means for independently regulating said several burners, a plurality of connections between adjacent ends of pairs of said heating tubes and cooperating with said heating tubes to form a heating coil extending along the longer horizontal axis of said chamber a distance substantially greater than the distance between adjacent burners, a stack flue beneath said chamber, 20 and means connecting said stack flue and said chamber along the longer axis of the floor of said chamber and between the innermost of said rows of heating tubes. 25

3. An oil heating furnace comprising a chamber rectangular in horizontal cross-section and substantially longer than wide, vertical heating tubes arranged in rows parallel to and spaced from the longer walls and the longer horizontal axis of said chamber, said rows being spaced substantially further from said axis than from the nearer of said walls, a plurality of fuel burners opening into said chamber between the innermost of said rows of heating tubes through a series of 30 ports spaced along the longer axis of said chamber, means for independently regulating said several burners, a plurality of connections between adjacent ends of pairs of said heating tubes and cooperating with said heating tubes to form 35 a heating coil extending along one of the longer side walls of said chamber a distance substantially greater than the distance between adjacent burners, a stack flue and means spaced along the longer axis of said chamber connecting 40 said stack flue and said chamber between the innermost of said rows of heating tubes. 45
